GARMENT

Christian H. Fleck, Jackson, Mich., assignor to
 S. H. Camp & Company, Jackson, Mich., a corporation of Michigan

Application September 7, 1937, Serial No. 162,580

1 Claim. (Cl. 2-43)

This invention relates to surgical garments and more particularly to a composite surgical garment for groin and thigh control designed for post-operative, pendulous abdomen and sacroiliac and general wear support.

In the usual garment of the above type wherein the lower edge is at the groin line when used by fleshy individuals surplus flesh bulges out at the lower edge. The present invention, by associating an overlapping skirt portion, which in no way interferes with the normal supporting features of the garment, overcomes the difficulty experienced as above described and at the same time provides an improved under abdominal and thigh line support.

An object of the invention is to provide a garment structure for giving smoother body lines.

Another object of the invention is to provide a new under-abdominal support and thigh control garment.

A further object of the invention is to provide a composite surgical garment for groin and thigh control having an overlying skirt portion which smooths out body lines and gives thigh control, yet, at the same time, is so constructed as to function independently of and without interference with proper groin support.

These and other objects will be apparent from the following specification when taken with the accompanying drawings in which

Fig. 1 is an inside view of the invention

Fig. 2 is an outside view of a portion of Fig. 1 particularly disclosing the skirt, and

Fig. 3 is an outside view similar to that of Fig. 2 disclosing the skirt of another embodiment of the invention.

Referring particularly to the drawings the reference character 1 indicates the center front or abdominal supporting portion or occupancy surface of the garment which is provided at one side with a plurality of fastening hooks 2 for engagement with the fastening eyes 3. As shown in Fig. 1 the fastening eyes 3 are protected from the body of the wearer by a soft strip 4. The top of the portion 1 comprises two elastic sections 5 anchored at their ends but separated from the fabric panels 6 of section 1. It will be observed that the top edges of the panels 6 are loose and of sufficient width to permit the elastic sections 5 to give release. The front portion 1 of the garment comprises a continuation of side portions 7 which are of generally the same depth as the front portion 1 and merge with the rear portion 8. The top edge of the rear portion 8 comprises a continuation of the side portions 7,

the lower edge of the rear portion 8, however, extending considerably below the lower extremity of the side portions 7 to a point substantially below the level of the groin region. Attached to the side portions 7 and the lower side edges 9 of the rear portion 8 are skirts 10. As disclosed particularly in Figs. 1 and 2 the top edges of the skirts 10 are of the same width as the side portions 7 and are secured approximately half way up the side portions 7 and to each side of the side portions 7. It should be observed, however, that sections 11 of the lower forward edges of the side portions 7 are free from the skirts 10, the skirts 10 being narrowed along the curved edge 10' and flared out at 10'' so that the lower corners 15 of the skirts 10 are in substantial vertical alignment with the forward edges of the side portions 7. As the lower edges of the side portions 7 in which the gussets 12 are located is below the point of attachment between the skirts 10 and the sections 11 and thus free from the skirts 10, release along this edge preventing binding is made possible. The side portions 7 are reinforced for lateral tension by reinforcing strips 13. Hose supporters 14 are slidably mounted on adjustable straps 15 each mounted at one end to the forward edge of a side portion 7 and at the other end to the corner 10'' of a skirt 10. Hose supporters 16 are slidably mounted on adjustable straps 17, the ends of which are mounted on spaced parts of the rear portions 8. The two back portions 8 are connected by lacing 18 of any usual style. Adjusting straps 19 and 19' are connected to the lacing 18 in any standard manner by means of running adjustment buckles 20, the adjustment straps 19 and 19' being secured to the garment at the intersections of side portions 7 and the rear portions 8. It is to be noted that the straps 19' act to give groin line support to that portion of the garment just above the gussets 12 and in the locality of the reinforcements 13.

When the garment is placed in position on the wearer and the hooks 2 engage with the eyes 3, it is tightened by taking up the free ends of the adjustment straps through the running adjustment buckles 20, drawing the halves of the rear portions 8 together. The hose supporters 14 and 16 when secured to the wearer's hose hold the garment down and the skirts 10 against the body. The arrangement of the skirts 10 in the garment are such that they in no way interfere with the proper groin support yet at the same time the skirts overlie that portion of the garment through which the supporting action along 55

the groin line is exerted, smoothing out the body lines at this point, and extending below to give thigh control.

Fig. 3 illustrates an embodiment of the invention wherein the structure is substantially the same as that disclosed in Figs. 1 and 2 with the exception of the adjusting straps 19 and 19' and the relation between the side portions and skirts. The adjusting straps 19 and 19' are secured to the garment at the forward edges of the side portions 7 instead of the rear edges. The lower adjusting straps 19' are secured to the garment between the skirts 25 and the side portions 26. To bring these straps to the outside of the garment, openings 27 are provided in the skirts 25 through which they pass. In order to distribute the tension of the lower adjusting strap 19' over a wider portion of the garment, it is secured to a flared portion 28 which is in turn secured to the garment. With respect to the relation between the side portions and skirts the skirts 25 are of greater width adjacent their lower portions than the overlapping portions of the side portions 26. This greater width permits a greater release by virtue of the gusset 28 than is obtained in the embodiment of the invention disclosed in Figs. 1 and 2 wherein the skirts 10 and the side portions 7 are of equal width at their overlapping areas. Otherwise the structure and operation of the garment disclosed in Fig. 3 is the same as that disclosed in Figs. 1 and 2.

Having thus described my invention what I desire to protect by Letters Patent and claim is:

A composite type garment for giving under abdominal uplift and thigh control characterized by its smooth contouring effect from the thigh upwardly through the groin line comprising an abdominal supporting and uplifting front portion, rear portions in spaced relation, side portions connecting said front and rear portions, said

front, side and rear portions having the top edges thereof in substantial alignment, adjustable lacing connecting said rear portions, tension strap portions connected to opposite sides of the lower part of said front portion and extending across said side portions, said strap portions having adjustment portions engaging with said lacing for imparting an under abdominal uplift and support to said front portion with the lateral tension of adjustment through said strap portions being across upper groin line, the lower edges of said side portions extending from opposite sides of the lower edge portions of said front portion across groin line to join said rear portions above the lower edges thereof but below the line of tension of said strap portions, skirt portions attached to said side portions along their upper edges on the outside of the garment substantially above the lower edges of said side portions, as well as above the line of lateral tension of said strap portions through said side portions, the sides of said skirt portions being connected to the sides of said front and rear portions with the lower edges of said skirt portion in substantial alignment with the lower edges of said rear portions, said skirt portions being free from and freely overlying the lower edges of said side portions and the zone of lateral tension through said side portions, and hose supporting structure having support-straps connected to said skirt portions to tension said skirt portions over the wearer's thigh to give thigh control and to tension said skirt portions to smooth out the contour line of the garment throughout that portion of the side portions over which said skirt portions freely lie without restricting the lateral tension through said side portions to said front portions thereby giving under abdominal support and uplift.

CHRISTIAN H. FLECK. 40
